(57) CLAIM

The ornamental design of a healthcare provider apron, as shown and described.

DESCRIPTION

FIG. 1 is a front view of an embodiment of a healthcare provider apron showing my new design;

FIG. 2 is a rear view of the healthcare provider apron of FIG. 1;

FIG. 3 is a front view of an alternate embodiment of a healthcare provider apron showing my new design; and,

In the drawing figures, the broken lines at the top left and right edges of the apron represent unclaimed subject matter. In FIGS. 1-4, the long dashed lines on the surface of the apron represent stitching.
